UNITED STATES PATENT OFFICE.

JONATHAN BEGG, OF OAKLAND, CALIFORNIA.

FLOATING BREAKWATER.

1,264,756.

Specification of Letters Patent. Patented Apr. 30, 1918.

Application filed August 9, 1917. Serial No. 185,295.

To all whom it may concern:

Be it known that I, JONATHAN BEGG, a citizen of the United States, residing at Oakland, in the county of Alameda and State 5 of California, have invented certain new and useful Improvements in Floating Breakwater, of which the following is a specification.

This invention relates to a floating breakwater and is particularly adapted for the 10 protection of stranded vessels.

One object of the invention is to provide a means whereby a film of oil may be distributed around the boat in an endeavor to 15 subdue the rough sea.

A further object is to provide within this oiled area a further protection in the form of a floating breakwater which has a still further tendency to lessen the impact of the 20 sea upon the stranded vessel.

In the accompanying drawings:

Figure 1 is a top plan view of the floating breakwater as applied when used,

Fig. 2 is an enlarged view of two of the 25 floating breakwater panels,

Fig. 2^a is a view of one of the anchors used in connection with the apparatus,

Fig. 3 is an enlarged view of one of the 30 clamping members,

Fig. 4 is an end view of one of the breakwater panels,

Fig. 5 is an enlarged sectional view showing the construction of the support for the outer pipe lines, and,

Fig. 6 is a cross section through the oil 35 spreading apparatus.

Numeral 1 indicates a series of logs of sufficient diameter which are adapted to be strung upon a cable 2 and extending substantially around a stranded ship. The ends of these logs are preferably capped with steel 40 rings 3 to prevent wear, and between the ends of each float are one or more flexible disks 4, which are adapted to act as bumpers to prevent wear on the ends of the floats. These logs may be made of any light material such as wood, yucca, or cylinders of copper or aluminum netting filled with cork, or they may also be made of strings of cork 45 with the cable passing therethrough.

The logs are held in place by anchors 5 being preferably cone-shaped, and provided with three or more metal legs 6, hinged to the outside and extending downwardly, the 55 body of the anchor being circular, hexagon, octagon or any other shape, but is preferably

cone-shaped. The top of the anchor may be closed with a swivel joint not shown and loop to accommodate a comparatively short cable 7, which is connected between the anchor and the main cable 2, which supports the floats. This cable 7 is preferably attached to the cable 2 by means of an adjustable clamp consisting of a body portion 8, with up-turned edges C, and a stud 8', eccentrically mounted between the up-turned edges whereby the cable 7, is wedged therebetween, thus providing means whereby the cable may be regulated as to its length according to the depth at the place they may be used.

Supported by the plurality of logs 1, is a plurality of steel pipes 9 jointed together by any suitable flexible joint such as ball and socket joints, rubber material or any suitable material as shown at 10. Extending inwardly from the several pipe sections is a plurality of perforated nozzles 11, which are preferably covered with canvas bags or other suitable muffler 12, the object being to break up the jets of oil, as much as possible, and cause the same to pass slowly into the sea.

These pipes are connected by suitable hose 13 and 14 to a pump or other suitable distributing means 15, arranged on the deck 85 of the vessel. These distributing means being preferably operated by motive power from the vessel, they may, however, be adapted to be operated by hand. In the arrangement as disclosed, these hose connections 13 and 14 are adapted to settle well below the surface of the water when leaving the ship in order to permit of the passage of the salvage boats to the inside of the outer link of pipes in order that they may get 90 alongside of the wreck. Where only one section of breakwater is required, the hose that connects with the oil distributing pipes can be made to float.

Arranged within the outer series of the oil distributing means is a section or inside breakwater arrangement consisting preferably of a series of frames 16, supported upon a continuous cable 17. This cable 17 is likewise anchored by a plurality of anchors 5, being connected thereto by short cables 18, which are similar in construction as the cable 7 previously described. These frames may be made any desired size, but are preferably approximately 6 feet 105 square, the frame portion being made of comparatively large timbers 19, the upper

horizontal ones of which are suitably reinforced and provided with a bore 20, to receive the supporting cable 17. The lower end of the vertical frame sections are provided with comparatively heavy U shaped metal weights 21, which are adapted to hold the several sections in a substantially vertical position. Within this frame are arranged a plurality of slats 22, the whole being reinforced by metal bolts 23 passing centrally through the frame. These frames are connected at their outer sections by suitable copper plated steel netting 24, which acts as a bearer at their outer sections, and tends to stiffen, somewhat, the floating breakwater in general and still allow a certain flexibility between the sections.

From the above it will be observed that I have provided comparatively similar and efficient means for the protection of a stranded vessel which can be thrown around the same in a comparatively short length of time and serve to give ample protection to the vessel during a storm and heavy seas arising therefrom.

It is obvious that this device may be used for many other purposes, as for instance, to protect landings where there is no actual protection.

30 I claim:

1. A floating breakwater consisting of an outer and inner line of floats, the outer floats carrying an oil distributing means, and the inner floats forming a substantially continuous wall within the outer floats.

2. A floating breakwater consisting of an outer and inner line of floats, the outer floats consisting of a plurality of float members connected together and supporting an oil distributing means, and the inner floats consisting of a plurality of floating frames connected together and weighted at their

lower extremities to hold them in a substantially vertical position.

3. A floating breakwater consisting of an outside protecting line of floats connected together, said floats adapted to support a flexible oil distributing means arranged in such a manner as to divert the oil inwardly therefrom, and an inner series of vertically disposed floats flexibly connected together.

4. A floating breakwater consisting of an outside protecting line composed of a string of floats flexibly connected together and adapted to support an oil distributing means consisting of a plurality of flexibly connecting pipes having inwardly projecting nozzles provided with an oil disseminating means, whereby the oil is spread evenly upon the surface of the water.

5. An oil floating breakwater consisting of a plurality of floating frames flexibly connected together and provided on their lower extremities with weights for holding them substantially in a vertical position, and anchors connected to said frames supporting means whereby the frames are held in a predetermined position.

6. A floating breakwater consisting of an outer and inner line of floats, the outer floats carrying a flexible pipe line provided with a plurality of inwardly projecting nozzles which are provided with an oil distributing means, whereby the oil is distributed evenly, and the inner floats consisting of a plurality of vertically disposed frames provided at their lower ends with weights, and connected at their outer sections with flexible connecting means, and anchors connected with said outer and inner line of floats, whereby the same are held in a predetermined position.

In testimony whereof I affix my signature.

JONATHAN BEGG.
